DRIVER'S HATCH CUPOLA FOR AN ARMORED VEHICLE

William A. Webb, Perry Hall, Md., assignor to Aircraft
Armaments, Inc., Cockeysville, Md., a corporation of
Maryland

Filed Jan. 21, 1960, Ser. No. 59,129

Term of patent 7 years

(Cl. D14—6)

FIG. 1

FIG. 2

FIG. 3

Figure 1 is a front perspective view of a driver's hatch cupola for an armored vehicle showing the new design with the hatch in closed position.

Figure 2 is a side perspective view of the cupola showing the hatch in open position.

Figure 3 is a top view of the cupola with the hatch in closed position.

I claim:

The ornamental design for a driver's hatch cupola for an armored vehicle, as shown.
